CLAIM

The ornamental design for a vehicle running board storage box with bulbous front edge, as shown and described.

DESCRIPTION

FIG. 1 is a front perspective view of the vehicle running board storage box with bulbous front edge showing my new design;

FIG. 2 is a front elevational view thereof;

FIG. 3 is a top plan view thereof;

FIG. 4 is a bottom plan view thereof;

FIG. 5 is a rear elevational view thereof; and,

FIG. 6 is an enlarged right side elevational view thereof with the left side being identical but reversed.
